SELENIUM DEPOSITING MACHINE

Cleveland Scudder Smith, Jr., West Orange, N. J., and Sol Blumenthal, Indianapolis, Ind.; said Smith assignor to Samuel Ruben, New Rochelle, N. Y., and said Blumenthal assignor to P. R. Mallory & Co., Inc., Indianapolis, Ind., a corporation of Delaware

Application September 5, 1945, Serial No. 614,517

14 Claims. (Cl. 91—12.2)

1

This invention relates to a coating machine and more particularly to a machine for the continuous deposition of a material such as selenium vapor onto a base plate, and has for an object to provide a machine of the above type having novel and improved characteristics.

In accordance with the present invention the base plates onto which the selenium is to be deposited are passed on a conveyor beneath a plurality of boilers which are arranged to vaporize the selenium and to discharge the vapor downwardly onto the upper surface of the plates as they pass thereunder. The boilers are arranged to deposit successive layers of selenium onto the base plate so that the deposit is built up to the desired thickness.

In one embodiment of the invention, a thin iron conveyor belt sliding over a glass support is held flat by a series of magnets which are placed beneath the conveyor. In the event the plates to be coated are of iron, the magnets serve also to position the plates accurately as they pass beneath the selenium boilers and suitable adjustments may be made for obtaining deposits having the desired characteristics. The machine also includes pre-heating means for heating the base plates prior to the deposition of the selenium and means to prevent the excess selenium from depositing on or contaminating the conveyor. In the embodiment shown, this last means comprises a web of paper or the like which is fed along with the conveyor beneath the plates on which the selenium is to be deposited.

Although the novel features which are believed to be characteristic of this invention are pointed out more particularly in the claims appended hereto, the nature of the invention will be better understood by referring to the following description taken in connection with the accompanying drawing in which a specific embodiment thereof has been set forth for purposes of illustration.

In the drawing:

Fig. 1 is a side elevation, partly in section, of a selenium depositing machine embodying the present invention;

Fig. 2 is a transverse section taken on the line 2—2 of Fig. 1 showing the arrangement of the selenium boilers;

Fig. 3 is a section taken on the line 3—3 of Fig. 1 showing the feed chute for supplying the base plates to the machine;

Fig. 4 is a perspective view of a base plate on which selenium is to be deposited; and

Fig. 5 is a section similar to Fig. 3 showing a modified form of feed chute.

2

Referring to the drawing more in detail, the machine is shown as embodying a framework 10, having a pedestal 11 carrying a driving roller 12 and a pedestal 13 carrying an idler roller 14. The conveyor belt 15 is passed around the rollers 12 and 14 and is driven thereby in the usual manner.

The driving roller 12 is mounted on a shaft 16 carrying a pulley 17 which is driven by a belt 18 from a driving pulley 19. The driving pulley 19 is mounted on a shaft 20 supported in brackets 21 attached to the frame 10 and is associated with a driving pulley 22 carrying a belt 23 which is driven by a pulley 24 attached to the shaft 25 of a driving motor 26. The motor 26 is likewise attached by a pedestal 27 to the frame 10. The pulleys 19 and 22 are of the speed regulating type and are so arranged that the speed of the conveyor 15 may be controlled as desired.

A roll 30 of paper or the like is mounted on brackets 31 carried by the frame 10 ahead of the idler roller 14. The web 32 of paper from the roll 30 passes onto the conveyor 15 and feeds along therewith, being deposited after passage over the roller 12 onto a suitable table 34. The web 32 may then be shredded and discarded or may be reeled upon a suitable take-off reel not shown.

The plates 40 to be coated (Figs. 3 and 4) are fed down the feed chute 41 (Figs. 1 and 3) by suitable means as by hand. The feed chute 41 comprises a bottom member 42 and side flanges 43 which are arranged to direct the plates 40 onto the conveyor 15. The conveyor is supported on longitudinal members 45 preferably of glass to position the same as it passes between the rollers 14 and 12. A plurality of permanent magnets 46 are provided beneath the members 45 in a position to hold flat the conveyor 15 as it carries plates to be coated under the boilers to be described. If the plates to be coated are of iron, these magnets 46 serve to hold the plates in a horizontal position so that the spacing thereof from the boilers may be accurately controlled. In that event the conveyor belt may be made of non magnetic material.

The boiler section comprises a plurality of boilers 50 which are arranged in succession beneath a hood 51. Each boiler 50 extends across conveyor 15 and is of the type designed to vaporize selenium and discharge the vapor downwardly from an elongated slit in the bottom of the boiler extending entirely across the conveyor. In the embodiment shown the boilers are indicated as comprising a plurality of vertically spaced trays

over which the liquid flows downwardly as it is vaporized, the conditions being maintained so that the liquid is completely vaporized before it reaches the bottom of the boiler. A boiler of this type is more fully disclosed in our co-pending application Serial No. 614,518 filed September 5, 1945, for Selenium boilers (M-1355).

As shown in Fig. 2, the boilers are heated by heating tubes 53 connected to a heater 54. The heating tubes may be heated in any suitable manner as by electrical resistance rods. Each boiler is provided with trunnions 56 carrying rollers 57 which engage in channels 58 positioned along the hood 51 so that the boilers may be spaced along the path of the conveyor as desired. The selenium is fed to each boiler from a hopper 60 by means of a screw conveyor 61 driven by a motor 62. The motor, hopper and conveyor are mounted on brackets 64 carrying rollers 65 which are supported on tracks 66 attached to the side of the hood, so that the feed mechanisms may be suitably adjusted to supply the material to the various boilers 50. The hood 51 is provided with a plurality of doors 67 through which the boilers may be adjusted and is provided with duct 68 leading to a suitable exhaust means not shown.

A pre-heating means, shown as a unit 70, is mounted ahead of the hood 51 adjacent the conveyor 15 so as to pre-heat the metal plates 40 before they pass to the boilers. The heat supplied to the plates by unit 70 may be generated by suitable means such as oxidation of combustible gases or electric heating elements and is shown as provided with connecting leads 71 by which heating current is supplied thereto.

In the operation of this machine the plates to be coated are supplied to the feed chute 41 by any suitable means and are deposited in succession on the conveyor 15. The web 32 of paper or the like is fed over the top surface of the conveyor 15 between the conveyor and the plates 40 and passes with the plates beneath the pre-heating unit 70 and the boilers 50 so as to prevent contamination of the conveyor by the selenium.

As the plates pass beneath the unit 70 they are pre-heated to a temperature suited for the efficient deposition of the selenium thereon. The boilers 50 are then adjusted so as to discharge the required quantity of vapor downwardly onto the upper surfaces of the plates 40 as they pass thereunder. The boilers should preferably be adjusted in close proximity to the upper surface of the plates 40 so that the vapors impinge directly on the plates as they emerge from the boilers. In this way contamination of the vapors is prevented and the vapors are most efficiently utilized. As the plates 40 pass beneath the boilers successive layers of selenium are deposited thereon until the deposit is built up to the desired thickness. The plates then pass from the hood 51 to the table 34 where they are discharged.

In the embodiment of Fig. 5 the chute 41 is provided with a plurality of channel members 80 which are arranged to guide a plurality of narrow plates 81 into the conveyor belt for treatment. This form permits a plurality of plates to be spaced and treated simultaneously.

It will be noted that the above machine is capable of operating continuously and that the selenium deposit may be varied as desired by suitable control of the feed of the conveyor 15 and of the size and distribution of the various selenium boilers 50. The selenium may of course be deposited onto a continuous strip if desired or may be deposited onto a succession of plates.

Although the machine is particularly adapted for the deposition of selenium, it is to be understood that it is not restricted thereto, but may be used for the deposition of other materials in liquid or vapor form. A specific embodiment of the invention has been shown only for purposes of illustration. The invention is only to be restricted in accordance with the scope of the following claims.

What is claimed is:

1. A machine for depositing a layer of material on a base member, comprising a conveyor for advancing said base member, a plurality of boilers spaced along the path of travel of said conveyor, said boilers having means to vaporize said material and to discharge the vapors onto the base member on said conveyor, and means to adjust the position of said boilers along said path for controlling the distribution of said material on said base member.
- 15 2. A machine for depositing a layer of material on a base member, comprising a conveyor for advancing said base member, a plurality of boilers spaced along the path of travel of said conveyor, said boilers having means to vaporize said material and to discharge the vapors onto the base member on said conveyor, a hood enclosing said boilers and means mounting said boilers on said hood for adjustment along said path.
- 25 3. A machine for depositing a layer of material on a base member, comprising a conveyor for advancing said base member, a plurality of boilers spaced along the path of travel of said conveyor, said boilers having means to vaporize said material and to discharge the vapors onto the base member on said conveyor, a web of disposable material and means feeding said web on said conveyor to protect the conveyor from said vapors.
- 35 4. A machine for depositing a layer of material on a base member, comprising a conveyor for advancing said base member, a plurality of boilers spaced along the path of travel of said conveyor, said boilers having means to vaporize said material and to discharge the vapors onto the base member on said conveyor, and a pre-heater disposed in advance of said boilers to pre-heat said member prior to deposition of the vapors thereon.
- 40 5. A machine for depositing a layer of material on a base member, comprising a conveyor for advancing said base member, a plurality of boilers spaced along the path of travel of said conveyor, said boilers having means to vaporize said material and to discharge the vapors onto the base member on said conveyor, and feed means associated with each boiler to supply thereto material to be vaporized.
- 45 6. A machine for depositing a layer of material on a base member, comprising a conveyor for advancing said base member, a plurality of boilers spaced along the path of travel of said conveyor, said boilers having means to vaporize said material and to discharge the vapors onto the base member on said conveyor, and feed means comprising a hopper and a screw conveyor extending along the top of each boiler to supply thereto material to be vaporized.
- 50 7. A machine for depositing a layer of material on a base member, comprising a conveyor for advancing said base member, a plurality of boilers spaced along the path of travel of said conveyor, said boilers having means to vaporize said material and to discharge the vapors onto the base member on said conveyor, feed means associated with each boiler to supply thereto ma-

terial to be vaporized, and means mounting said feed means for adjustment with said boilers along said path.

8. A machine for depositing a layer of material on a succession of base members, comprising a belt conveyor for advancing said base members, means driving said conveyor, means for adjusting the speed of said conveyor, a roll of web material, means mounting said roll to feed said web along said belt and a plurality of boilers spaced along the path of travel of said conveyor, said boilers having means to vaporize said material and to discharge the vapors onto the base member on said conveyor, and means discharging said base members with said web after passage beneath said boilers.

9. A machine for depositing a layer of material on a succession of base members, comprising a belt conveyor for advancing said base members, means driving said conveyor, a roll of web material, means mounting said roll to feed said web along said belt, and a plurality of boilers spaced along the path of travel of said conveyor, said boilers having means to vaporize said material and to discharge the vapors onto the base member on said conveyor, and means discharging said base members with said web after passage beneath said boilers.

10. A machine for depositing a layer of material on a succession of base members, comprising a belt conveyor for advancing said base members, means driving said conveyor, means for adjusting the speed of said conveyor, a roll of web material, means mounting said roll to feed said web along said belt, and a plurality of boilers spaced along the path of travel of said conveyor, said boilers having means to vaporize said material and to discharge the vapors onto the base member on said conveyor, means to adjust the position of said boilers along said path for controlling the distribution of said material on said base member, and means discharging said base members with said web after passage beneath said boilers.

11. A machine for depositing a layer of material on a succession of base members, comprising a belt conveyor for advancing said base members, means driving said conveyor, means for adjusting the speed of said conveyor, a roll of web material, means mounting said roll to feed said web along said belt, and a plurality of boilers spaced along the path of travel of said conveyor, said boilers having means to vaporize said material and to discharge the vapors onto the base member on said conveyor, means discharging said base members with said web after passage beneath said boilers, a hood enclosing said boilers, and means mounting said boilers on said hood for adjustment along said path.

12. A machine for depositing a layer of material on a succession of base members, comprising

a belt conveyor for advancing said base members, means driving said conveyor, means for adjusting the speed of said conveyor, a roll of web material, means mounting said roll to feed said web along said belt, and a plurality of boilers spaced along the path of travel of said conveyor, said boilers having means to vaporize said material and to discharge the vapors onto the base member on said conveyor, means discharging said base members with said web after passage beneath said boilers, and a preheater disposed in advance of said boilers to pre-heat said member prior to deposition of the vapors thereon.

13. A machine for depositing a layer of material on a succession of base members, comprising a belt conveyor for advancing said base members, means driving said conveyor, means for adjusting the speed of said conveyor, a roll of web material, means mounting said roll to feed said web along said belt, and a plurality of boilers spaced along the path of travel of said conveyor, said boilers having means to vaporize said material and to discharge the vapors onto the base member on said conveyor, means discharging said base members with said web after passage beneath said boilers, and feed means associated with each boiler to supply thereto material to be vaporized.

14. A machine for depositing a layer of material on a succession of base members, comprising a belt conveyor for advancing said base members, means driving said conveyor, means for adjusting the speed of said conveyor, a roll of web material, means mounting said roll to feed said web along said belt, and a plurality of boilers spaced along the path of travel of said conveyor, said boilers having means to vaporize said material and to discharge the vapors onto the base member on said conveyor, means discharging said base members with said web after passage beneath said boilers, and feed means comprising a hopper and a screw conveyor extending along the top of each boiler to supply thereto material to be vaporized.
